UNITED STATES PATENT OFFICE

2,421,562

APPARATUS FOR HEATING OIL AND OTHER
FLUID MEDIA

Lee P. Hynes, Haddonfield, N. J.

Application May 10, 1944, Serial No. 534,975

13 Claims. (Cl. 219—39)

1

This invention is an apparatus for heating a body of circulating fluid medium.

One of the objects of the invention is to provide a simple heating apparatus in which the medium to be heated, in the form of a more or less flat stream, is caused to travel in a continuous circulation course over the entire area of the exposed heating surface. A further object is to provide a heater of the character mentioned so constructed and arranged as to provide for ready access to the interior of the heating chamber, without the necessity of removing the heat exchange units or the heating elements associated therewith. Another object is to provide simple and effective means for supporting the heat exchange units in such manner as to provide a maximum of heating area, and at all times and under all conditions of operation, to protect the terminals of the heater elements associated therewith from direct contact with the fluid medium being treated. An additional object is to provide heater elements which may be readily detached from the heat exchange units so that repairs and replacements may be made without disturbing said units.

The invention will be hereinafter fully set forth and particularly pointed out in the claims.

In the accompanying drawing:

Figure 1 is a top plan view illustrating a heater constructed in accordance with the invention.

Figure 2 is a vertical sectional view on the line 2—2, Figure 1.

Figure 3 is a vertical transverse sectional view on the line 3—3, Figure 1.

Figure 4 is a detail view illustrating the arrangement of the baffle plate structure.

Figure 5 is a detail sectional view illustrating a modified means of supporting the heat exchange members.

Figure 6 is a sectional view illustrating a slight modification.

Referring to the drawing, 10 designates a U-shaped casing having the edges of its open side welded to a metal frame 11. Said frame is provided with a cut-out portion 12, which is normally closed by a cover plate 13, removably attached to the frame 11 by means of bolts or similar devices 14. A gasket 15 is interposed between the cover plate and the frame 11 so as to maintain a liquid tight joint while the cover plate is in position.

The ends of the casing 10 are closed by end plates 20, 20a, which are welded or otherwise secured to the adjacent end portions of the casing 10 and frame 11. Said plates 20 are provided

5 with transverse slots 21 each arranged to receive the open ends of tubular partition-like, heat transfer members H. Any desired number of these heat transfer members H may be employed, but for purposes of illustration three such members 23, 24 and 25 are shown. The open end of each member 23 and 25 is extended through a complementary slot of end plate 20, the open end of the unit 24 being mounted in a corresponding slot of the end plate 20a. The heat-exchange members are welded or otherwise sealed to their respective end plates. From what has been said, it will be readily understood that the heat-exchange members 23, 24 and 25 extend longitudinally of the casing in staggered relationship and that they also extend transversely the full width of the casing 10. They are also in the form of flat tubes which function as transverse partitions, the top and bottom surfaces of which provide substantial heating areas exposed to contact with the circulating fluid medium to be heated. Thus they provide a tortuous channel between the inlet a and the outlet b, through which the fluid to be treated must travel in contact with a maximum area of heating surface.

10 The cover plate 13 while secured in operative position, will not engage the adjacent edges of the tubular members 23, 24 and 25. The space between the cover plate and the heat exchange members may be filled in any desired manner. For purposes of illustration, the cover plate is shown in Figure 3 as provided with a filler plate 26, positioned to bear against the adjacent portions of the heat exchange members 23, 24 and 25 and thereby prevent leakage of fluid around them. In this arrangement the gasket 15 extends around the edges of the filler plate. In lieu of providing the cover plate with a filler plate, the combined functions of the gasket and filler plate 15 may be performed by enlarging the gasket, as shown in Figure 6. Referring to said figure, the gasket 15 is provided with a filler portion 15a of the same material, secured thereto in suitable manner, as by rivets 15b.

15 It is preferred to employ electric heater units 27 which are located within the tubular members. The outer ends of the units 27 are provided with electrical terminals, the latter end being extended into terminal boxes 28, one at each end of the casing. Each of the end walls 20, 20a forms a wall of said terminal box. Said box is provided with a connection 30 for passage of electric cables into the box, so as to bring the electrical circuit wires to a position where they may be connected to the terminals 31 of the heaters. These heater

units may be either fixedly secured within the partition tubes or they may be removable, if desired. It is preferred to employ the removable type because of the advantage of easy replacement, if and when necessary. One wall of each box or chamber 28 is provided with an opening 29, normally closed by a removable cover 33 sealed by a suitable gasket.

To maintain the heat exchange members in properly spaced relation with respect to each other, a cross-member 32 is preferably welded to the closed end of each tube 23, 24 and 25. This cross-member is narrow and does not interfere with or impede the proper flow of fluid around the closed ends of the heat-exchange members, but it serves to center the latter with relation to each other, and with respect to the top and bottom tubes it also serves to center the latter between the outer casing and the next tube. In lieu of the cross members 32, the tubes H may be supported by sectional channels 32^a, 32^b (see Fig. 5), which are suitably secured to the rear wall of the casing and to the filler piece 26, respectively. It will be observed that in this instance, the filler piece is reduced in thickness to accommodate the thickness of the channels 32^b, so that when the filler piece is in position it will line up with the inside of frame 11. Under some conditions the channels 32^b may be omitted, in which event the filler piece will be of sufficient thickness to directly engage the adjacent edges of the tubes H, similar to the manner shown in Figure 4.

A very important factor in the heating of liquids is the velocity of flow of the liquid over the heat transfer surfaces. With many fluids it is necessary to greatly increase the velocity of flow over that which would be entirely satisfactory for other fluids. In addition to the great variation in fluids themselves, heaters are required to handle various quantities of a given fluid per unit of time. For instance, it may be necessary to pump through a heater as little as 25 gallons per hour in one case, and in another installation to pump 100, 500 or even 1,000 gallons per hour. For the larger volumes, ample velocity of flow can usually be obtained, but for small volumes it is necessary to find some way to increase the velocity of the flow, and the best method is to reduce the internal cross sectional area of the fluid passage of the heater. It is not feasible to make a new design for each desired rate of flow, and in many instances it would be impracticable to space the tubes closely enough together to give a small enough cross sectional area of the fluid passage. To meet this condition, a series of baffles 35 attached to base members 36 are provided. The base members are slidingly insertable between adjacent pairs of tubes H, and if desired they may be removably secured to the back wall 37 of the casing 10 by bolts 36^a as indicated in Figure 4. A similar assembly of baffles 38 can likewise be inserted into the fluid passages between the tubes 23, 24 and 25, by attaching the same to the filler plate 26. These baffles are arranged in definitely spaced staggered relation to each other, and it is very simple to design them for any desired area of cross section of fluid flow. Thus baffles of this type may be introduced to give any desired velocity of fluid flow through the heater passage. To change this flow it is only necessary to insert a different set of baffles having different relative spacing. When cleaning the casing is

5 desired, the baffles 38 will be removed with the filler plate 26, to which it is attached.

In operation, the heater units 27 are inserted in the respective heat transfer tubes 23, 24 and 25, and the desired sets of baffles 35 and 38 are properly located within the casing 10. The fluid to be heated is caused to enter the casing through the inlet a, and under sufficient pressure to cause it to flow back and forth longitudinally of the casing over the baffles at the desired speed, and in contact with the heat transfer surfaces of said tubes 23, 24 and 25, until it passes out the outlet b.

10 The advantages of the invention will be readily understood by those skilled in the art to which it belongs. For instance, it will be observed that a very simple and inexpensive form of heater is provided, whereby the fluid to be heated is caused to travel from the inlet to the outlet in contact with staggered heat exchange units, in the form of a more or less flat stream, the velocity of flow of said fluid being controlled by a simple arrangement of preselected baffle plates provided for that purpose.

15 A further important advantage is that the terminals for the electric heater units are so located that they are at all times isolated from the fluid which is being circulated through the heater, so that broken pipes or other leaks will not cause any damage to the electrical connections. It will also be observed that the heater may be conveniently cleaned, or exposed to inspection upon removing the cover plate, and without the necessity of shutting off the electric power or disconnecting the heater units. In other words, it is possible to work around the interior of the casing without danger of electric shock, although the control switch to the circuits should be cut off so that the heater is not too hot to work on.

20 However, there are times in cleaning out heavy or gummy materials when some heat should be temporarily applied in order to make the material fluid enough to remove. The present invention has the advantage that the current may be turned on at any time for just the amount of temperature rise inside the heating casing which may be required to produce the desired fluidity of the refuse which is to be removed.

25 Having thus explained the nature of the invention and described an operative manner of constructing and using the same, although without attempting to set forth all of the forms in which it may be made, or all of the forms of its use, what is claimed is:

30 1. A heating apparatus of the character described having in combination a casing provided with an inlet and an outlet, a plurality of flat, flow-directing partitions each of a width extending transversely across the casing from the front wall to the rear wall thereof and of a width to contact with said walls, said partitions being shorter than the length of the casing and extending longitudinally of the casing from the respective ends thereof and in alternate relationship, each partition having one end extended through and sealed to and supported by an end wall of the casing, the other end thereof terminating at a position adjacent to the other end wall of said casing, so as to provide a continuous tortuous channel from the inlet to the outlet, baffles located between the respective partitions to control the velocity of flow of the fluid through said channel, and means for independently heating each of said partitions.

35 2. A heating apparatus of the character de-

scribed having in combination a casing provided with an inlet and an outlet, a plurality of flat, flow-directing partitions each of a width extending transversely across the casing from the front wall to the rear wall thereof, said partitions being shorter than the length of the casing and extending longitudinally of the casing from the respective ends thereof and in alternate relationship, each partition having one end sealed to and supported by an end wall of the casing, the other end thereof terminating at a position adjacent to the other end wall of said casing, so as to provide a continuous tortuous channel from the inlet to the outlet, baffles extended in opposite directions from said front and rear walls, respectively, and into the spaces between the respective partitions and in staggered relationship so as to control the velocity of flow of the fluid through said channel, and means for independently heating each of said partitions.

3. A heating apparatus of the character described having in combination a casing provided with an inlet and an outlet, a plurality of flat, flow-directing partitions each of a width extending transversely across the casing from the front wall to the rear wall thereof, said partitions being shorter than the length of the casing and extending longitudinally of the casing from the respective ends thereof and in alternate relationship, each partition having an open end extended through and sealed to and supported by an end wall of the casing, the other end thereof terminating at a position adjacent to the other end wall of said casing, so as to provide a continuous tortuous channel from the inlet to the outlet, baffle members removably secured within the casing and extending in opposite directions between the respective partitions and in staggered relationship with respect to each other, so as to control the velocity of flow of fluid through said channel, and means insertable through the open ends of said partitions for independently heating each of said partitions.

4. A heating apparatus of the character described having in combination a casing provided with an inlet and an outlet, a plurality of flat, flow-directing partitions each of a width extending transversely across the casing from the front wall to the rear wall thereof, said partitions being shorter than the length of the casing and alternately extending longitudinally of the casing from the respective end walls thereof, so as to provide a continuous tortuous channel from the inlet to the outlet, each partition being in the form of a flat tube open at one end, the other end thereof being closed, the open end of each tube being extended through and sealed to an end wall of the casing, the closed end of the tube terminating at a position adjacent the other end wall of the casing, a removable front wall for said casing having a portion bearing against the adjacent edges of the partitions, closed chambers attached to said end walls, and independent heating units insertable into the respective partitions through the open ends thereof and each having a terminal portion extending from the open end of its partition and through the adjacent end wall into said closed chambers.

5. A heating apparatus of the character described having in combination a casing provided with an inlet and an outlet, a plurality of flat, flow-directing partitions each of a width extending transversely across the casing from the front wall to the rear wall thereof, said partitions being shorter than the length of the casing and alter-

nately extending longitudinally of the casing from the respective end walls thereof, so as to provide a continuous tortuous channel from the inlet to the outlet, each partition being in the form of a flat tube open at one end, the other end thereof being closed, the open end of each tube being extended through and sealed to an end wall of the casing, the closed end of the tube terminating at a position adjacent the other end wall of the casing, a removable front wall for said casing having a portion bearing against the adjacent edges of the partitions, velocity-flow-control baffles removably attached to the rear wall of the casing and extended transversely across the casing between said partitions, similar baffles secured to the removable front wall of the casing and staggered with respect to the first mentioned baffles, and independent heating elements located within the respective partitions and extending through the respective end walls of the casing.

6. A heating apparatus of the character described comprising a rectangular enclosure having an inlet and an outlet, flat, parallel flow-directing partitions located within said casing and arranged so as to close the space between the front and rear walls thereof, said partitions being shorter than the length of the casing and arranged in alternate relationship, each having one end sealed to an end wall of the chamber, so as to form a relatively shallow flat walled tortuous passage for fluid from the inlet to the outlet, a removable front wall for said chamber having means for releasably engaging and sealing against the adjacent side of each of said partitions, sealed chambers connected with the end walls of said casing, electrical heating elements for independently heating said partitions and each having a terminal portion located in a sealed chamber, each chamber being provided with a removable portion to give access to said terminals.

7. A heating apparatus of the character described having in combination a casing provided with oppositely disposed front and rear walls, a removable cover member for said opening, said front wall having an opening therein, said casing having an inlet and an outlet, a plurality of flat, flow-directing partitions each of a width extending transversely across the casing from the front wall to the rear wall thereof, said partitions being shorter than the length of the casing and extending longitudinally of the casing from the respective ends thereof and in alternate relationship, each partition having one end sealed to and supported by an end wall of the casing, the other end thereof terminating at a position adjacent to the other end wall of said casing, so as to provide a continuous tortuous channel from the inlet to the outlet, means for independently heating each of said partitions, and a filler member located within the opening of said front wall and interposed between the cover member and said partitions, said filler member being positioned to releasably engage and seal the adjacent edges of the said partitions.

8. A heating apparatus of the character described having in combination a casing provided with oppositely disposed front and rear walls, said front wall having an opening therein, said casing having an inlet and an outlet, a plurality of flat, flow-directing partitions each of a width extending transversely across the casing from the front wall to the rear wall thereof, said partitions being shorter than the length of the casing and

extending longitudinally of the casing from the respective ends thereof and in alternate relationship, each partition having one end sealed to and supported by an end wall of the casing, the other end thereof terminating at a position adjacent to the other end wall of said casing, so as to provide a continuous tortuous channel from the inlet to the outlet, means for independently heating each of said partitions, and a gasket extending over the open portion of the front wall and interposed between the cover plate and said front wall, said gasket having a filler portion extended through said open portion, said filler member being positioned to releasably engage and seal adjacent edges of said partitions.

9. A heating apparatus of the character described having in combination a casing provided with an inlet and an outlet, said casing having a rear wall and a removable front wall, a plurality of flat, flow-directing partitions each of a width extending transversely across the casing from the front wall to the rear wall thereof, said partitions being shorter than the length of the casing and extended longitudinally of the casing from the respective ends thereof and in alternate relationship, each partition having an open end extended through and sealed to an end wall of the partition, the other end of each casing being closed and located at a position adjacent to the other wall of said casing, so as to provide a continuous tortuous channel from the inlet to the outlet, means engaging the closed ends of said partitions for supporting said partitions in centered relation with respect to each other, and means for independently heating each of said partitions.

10. A heating apparatus of the character described having in combination a casing provided with an inlet and an outlet, said casing having a rear wall and a removable front wall, a plurality of flat, flow-directing partitions each of a width extending transversely across the casing from the front wall to the rear wall thereof, said partitions being shorter than the length of the casing and extended longitudinally of the casing from the respective end thereof and in alternate relationship, each partition having the form of a flat tube with an open end extended through and sealed to an end wall of the casing, the other end of each casing being closed and located at a position adjacent to the other wall of said casing, so as to provide a continuous tortuous channel from the inlet to the outlet, longitudinally disposed angle members supported by the rear wall and releasably engaged with said partitions at one edge thereof, so as to support the latter in centered relation with respect to each other, means carried by said removable end wall for releasably engaging the adjacent edges of said partitions, and means for independently heating each of said partitions.

11. A heating apparatus of the character described having in combination a casing provided with an inlet and an outlet, said casing having a rear wall and a removable front wall, a plurality of flat, flow-directing partitions each of a width extending transversely across the casing from the

front wall to the rear wall thereof, said partitions being shorter than the length of the casing and extended longitudinally of the casing from the respective end thereof and in alternate relationship, each partition having an open end extended through and sealed to an end wall of the casing, the other end of each casing being closed and located at a position adjacent to the other wall of said casing, so as to provide a continuous tortuous channel from the inlet to the outlet, longitudinally disposed angle members supported by the rear wall and releasably engaged with said partitions at one edge thereof, similar angle members carried by the removable front wall and releasably engageable with the adjacent edges of said partitions, said angle members supporting said partitions in centered relation with respect to each other, and means for independently heating said partitions.

12. A heating apparatus of the character described having in combination a casing provided with an inlet and an outlet, a removable front wall for said casing, a plurality of flat flow-directing partitions each of a width extending transversely across the casing from the said front wall to the rear wall thereof, each partition having one end supported by an end wall of the casing, the other end thereof terminating at a position adjacent to but spaced from the other end wall of the casing so as to provide a continuous tortuous channel from the inlet to the outlet, means on a wall of said casing coextensive with said partitions to seal the same with said wall and to maintain said partitions in relatively spaced positions within said casing, and means for independently heating each of said partitions.

13. A heating apparatus of the character described comprising a rectangular casing having a rear wall and a removable front wall, an inlet and an outlet for said casing, flat parallel flow-directing partitions projecting into said casing from the ends thereof, said partitions being shorter than the length of said casing and arranged in alternate relationship so as to form a flat walled tortuous passage for fluid from the inlet to the outlet, means on the rear wall of said casing to hold said partitions at all times in spaced relationship and liquid sealed with said rear wall, sealing means on said front wall to seal the latter with the casing and to seal the wall with the adjacent edges of said partitions, and electrical heating elements in said partitions.
